UNITED STATES PATENT OFFICE.

WILLIAM T. ROBERTSON, OF MONTGOMERY, ALABAMA.

CIGAR-BOX.

SPECIFICATION forming part of Letters Patent No. 396,114, dated January 15, 1889.

Application filed November 30, 1888. Serial No. 292,243. (No model.)

To all whom it may concern:

Be it known that I, WILLIAM T. ROBERTSON, a citizen of the United States, residing at Montgomery, in the county of Montgomery and State of Alabama, have invented certain new and useful Improvements in Cigar-Boxes; and I do hereby declare the following to be a full, clear, and exact description of the invention, such as will enable others skilled in the art to which it appertains to make and use the same.

My invention relates to an improvement in cigar-boxes and other receptacles.

Heretofore cigar-boxes have been provided with a false bottom adapted to be raised and lowered from time to time for the purpose of keeping its contents up flush with the top of the box to give it the appearance of being full; but in the old devices the mechanism was such that every box or receptacle using them had to be made to suit the mechanism for raising and lowering the bottom.

The object of my invention is to provide a false bottom with such attachments that it can be readily applied to boxes of various sizes and shapes without requiring any change whatever in the box itself; and a further object is to produce a much more simple, cheap, durable, and easily operated device than those heretofore in use.

With these ends in view my invention consists in the peculiar arrangement and combination of parts, more fully described herein-after, and pointed out in the claims.

Referring to the accompanying drawings, Figure 1 denotes a side elevation of my invention as applied to a common cigar-box; Fig. 2, a similar view showing the false bottom in raised adjustment; Fig. 3, a detail view showing the false bottom separated from the box, and Fig. 4 a modification in which the bails are constructed differently.

The reference-letter *a* indicates an ordinary box provided with a false bottom, *b*, arranged to have a free vertical movement within the box. Attached to and forming part of the false bottom are the upright bails *c*, which are given a length less than the height of the box to enable the false bottom and bails to be wholly inclosed within the box when the latter is filled, as shown in Fig.

1. Thus, when the box is packed full and ready for shipment its exterior is entirely free from objectionable projections, which might themselves become injured or injure the contents of the box by coming in contact with other articles in transit. 55

The bails are by preference made out of thin strips of tin or other similar pliable metal or substance, and their length regulated according to the depth of the box calculated to receive them. The lower ends of the bails may be tacked or otherwise suitably fastened to the sides or ends of the bottom by nails *g*, or fastened in any suitable manner. 65 It may be found convenient to provide bails in the form of loops *h*, or to provide a pair of bails upon opposite sides of the bottom, as shown at *c c* in Fig. 4. I prefer, however, to make the bails of flat pliable tin strips, so 70 that when their free ends are bent over the sides of the box the flat surface of the tin will form a wider bearing upon the upper edge of the box to prevent the false bottom from swinging laterally. This objection 75 would also be overcome by the loops and double bails previously described.

In using my device the false bottom is first placed within the box so as to rest upon the rigid bottom of the same, and when in this 80 position the bails throughout their entire length lie against the inner sides and wholly within the receptacle. As its contents are removed, the bottom can be gradually elevated and held at any desired height by simply lifting up on the free ends of the bails and then bending or folding them down over the upper edge of the box, in which position they are shown in Fig. 2. Thus the box can be made to have the appearance of being full when 90 enough of its contents are left to cover the false bottom. 85

It is evident that many slight changes which might suggest themselves to a skilled mechanic could be resorted to without departing from the spirit and scope of my invention; hence I do not limit myself to the precise construction herein shown. 95

Having thus described my invention, what I claim as new, and desire to secure by Letters Patent, is— 100

1. In a receptacle, a false bottom, in combi-

nation with pliable bails adapted to lie wholly within the receptacle when not in use and to be bent over the upper edges of same when in use, in the manner and for the purpose substantially as described.

2. In a receptacle, a false bottom, in combination with pliable bails secured to the bottom and arranged to lock over the upper edges of the receptacle for holding the bottom at various heights, in the manner and for the purpose described.

3. The herein-described false bottom, provided with pliable metallic bails secured di-

rectly thereto, in the manner and for the purpose set forth. 15

4. The herein-described false bottom, provided with flat pliable metallic bails secured to its opposite sides, in the manner and for the purpose substantially as described.

In testimony whereof I affix my signature in 20 presence of two witnesses.

WILLIAM T. ROBERTSON.
